UNITED STATES PATENT OFFICE.

WALTER CHAS. SCHROECK AND WILLIAM LISSMANN, OF CHICAGO, ILLINOIS.

VALVE LATHE.

Application filed November 24, 1922. Serial No. 603,064.

To all whom it may concern:

Be it known that we, WALTER CHARLES SCHROECK and WILLIAM LISSMANN, both citizens of the United States, and residents 5 of Chicago, in the county of Cook and State of Illinois, have invented a new and useful Improvement in Valve Lathes, of which the following is a full, clear, and exact description.

10 Our invention relates to improvements in valve lathes, and it consists in the combinations, constructions, and arrangements herein described and claimed.

An object of our invention is to provide 15 a valve lathe which is adapted to accurately cut a valve to an angle of 45 degrees, and which has means for rotating the valve and for moving the cutter with respect to the valve during the cutting operation.

20 A further object of our invention is to provide a device of the character described which has a novel chuck for holding the valve.

A further object of our invention is to 25 provide a device of the character described which has novel means for moving the cutter with respect to the valve and for holding the cutter in adjusted position.

A further object of our invention is to 30 provide a device of the character described which has automatic means for moving the cutter at an angle of 45 degrees to the valve while the cutting operation is being accomplished, whereby the valve is provided with an edge which is accurately disposed at 45 degrees with respect to the longitudinal axis 35 of the valve.

A further object of our invention is to 40 provide a device of the character described which is relatively simple in construction and which makes use of common means for rotating the valve and for moving the cutting member along the valve during the grinding operation.

45 Other objects and advantages will appear in the following specification, and the novel features of the invention will be particularly pointed out in the appended claims.

Our invention is illustrated in the accom-

panying drawings, forming part of this application, in which

Figure 1 is a plan view of the device.

Figure 2 is a section along the line 2—2 of Figure 1.

Figure 3 is an enlarged detailed view of 55 the chuck, portions thereof being broken away, and

Figure 4 is a section along the line 4—4 of Figure 3.

In carrying out our invention, we provide 60 a base 1 which carries integral bearings 2 and 3. These bearings are alined and are adapted to support a shaft 4 which is rotatably disposed therein. The shaft 4 carries a novel chuck 5 to be hereinafter described, 65 and also carries a beveled gear 6. Collars 7 and 8 are rigidly secured to the shaft and bear against the sides of the bearing 2, thereby preventing longitudinal movement of the shaft 4 with respect to the bearings 70 2 and 3. A crank handle 9 is secured to the free end of the shaft 4 and is adapted to rotate the shaft.

The base 1 also carries bearings 10 and 11. A stub shaft 12 (see Figure 2) is rotatably carried by the bearings 10 and 11 and supports a beveled gear 13 which is in mesh with the gear 6 and also supports a gear 14. The gear 14 is rigidly secured to the stub shaft 12 and is adapted to rotate 80 when the gear 13 is rotated. It is to be noted that the stub shaft 12 extends at an angle of 45 degrees to the axis of the shaft 4.

A shaft 15 is disposed beneath the stub shaft 12 (see Figure 2) and lies in the same 85 plane. The shaft 15 extends beneath the chuck 5 and is adapted to move a cutter carrying member 16. The member 16 is slidably mounted on guide members 17 and is adapted to be moved along the guide members. The end of the shaft 15 is threaded at 18 and is received in a threaded bore (not shown) in the member 16, whereby rotation of the shaft 15 will move the member 16 90 along the guides 17. A screw 19 extends at 95 right angles to the shaft 17 and is carried by the member 16. A cutter vice 20 is slidably carried by the member 16 and is adapt-

ed to move at right angles to the shaft 15. A rotation of the screw 19 by means of a crank handle 21 will move the vice 20 along the member 16. The vice 20 adjustably carries a cutter 22.

Rotation of the shaft 15 will move the cutter 22 in the direction of the longitudinal axis of the shaft, while a rotation of the shaft 19 will move the cutter in the direction of the shaft 19 and at right angles to the longitudinal axis of the shaft 15.

From the foregoing description of the various parts of the device, the operation thereof may be readily understood. When it is desired to grind a valve 23, a cutter 22 is disposed in the vice 20 and the vice is moved by means of the screw 19 and the shaft 15 so as to position the cutter adjacent to the outer edge of the valve 23. It will now be observed that when the crank 9 is rotated, the valve 23 will be rotated and the cutter 22 will be moved along the surface 24 of the valve by means of the shaft 15 and member 16. The shaft 15 is operatively connected to the stub shaft 12 by means of a gear 25 which is in mesh with the gear 14. During the grinding operation, the valve 23 is rotated and the cutter 22 is moved at an angle of 45 degrees to the longitudinal axis of the valve, the cutter all the time engaging with the surface 24 of the valve. It will therefore be apparent that the valve will be provided with a surface 24 that extends at an angle of 45 degrees to the axis of the valve. The movement of the cutter and the rotation of the valve 23 are adjusted so as to rotate the valve at the desired speed with respect to the cutter. The cutter 22 gradually works its way along the side 24 of the valve during the cutting operation and it will be obvious that the valve 23 will be rotated through a number of revolutions as the cutter is gradually moved along the side 24.

In Figure 4 we have shown a novel chuck for holding the valve 23. It will be noted that the shaft 4 is threaded at 30 and receives two knurled nuts 31 and 32. The inner faces of the nuts 31 and 32 are provided with cam-shaped recesses 33 and 34, respectively. A sleeve 35 is loosely mounted upon the threads 30 and has grooves 36 therein which are aligned with the grooves 36 (see Figure 4). Dogs 37 are disposed in the grooves 36. The dogs 37 have outwardly extending ends 38 which are received in the recesses 33 and 34. The shaft 4 has slots 39 therein which extend inwardly from the end of the shaft 4. It is obvious from this construction that a rotation of the nuts 31 and 32 so as to move the nuts toward each other will cause the dogs 37 to move toward the longitudinal axis of the shaft 4 and to grip the stem of the valve 23.

In assembling the parts of the chuck

together, the dogs are first disposed in the slots 39 and then are aligned with the grooves 36 of the sleeve 35 to permit the sleeve to be passed over the dogs and be received in the bearing 3. The nut 31 is rotated so as to dispose the ends 38 in the recess 33. The nut 32 is now disposed upon the shaft 4 and is rotated so as to receive the other ends 38 of the dogs 37. The chuck is now ready to rigidly hold a valve 23 therein. When there is no valve disposed within the chuck, the dogs are free to move toward or away from each other. The cam surfaces 40 of the dogs are adapted to move the dogs outwardly when the stem of the valve 23 is disposed in the bore of the shaft 4. After the stem of the valve 23 is disposed within the chuck 5, the nuts 31 and 32 may be rotated so as to be moved toward each other, whereupon the cam sides of the slots 33 and 34 will engage with the dogs 37 to move them into gripping engagement with the stem of the valve 23. The valve is now rigidly held in position and moreover is automatically alined with the axis of the shaft 4. When the shaft 4 is rotated by means of the crank 9, the chuck rotates in the bearing 3. In this instance, the sleeve 35 acts as a bushing for the chuck. The chuck is very novel in construction and consists of a minimum number of parts which are adapted to automatically grip and aline a valve with the axis of the shaft 4 when the nuts 31 and 32 are rotated.

The cutter feeding means and the chuck co-act to provide a device which is very efficient for the purpose intended. The device may be manually or machine operated and in the present instance, is actuated by the crank 9. The device is readily portable, since it is mounted upon a base that may be readily moved.

We claim:

1. A valve lathe comprising a base, shaft carrying bearings projecting upwardly from said base, a hollow shaft having a slotted end, valve stem engaging members disposed in said slots, a sleeve mounted on the slotted end of said shaft and having grooves to receive said members, said sleeve being mounted in one of said bearings and said shaft being mounted in another bearing, and means for moving said members into engagement with a valve stem.

2. A valve lathe comprising a base, shaft carrying bearings projecting upwardly from said base, a hollow shaft having a slotted end, valve stem engaging members disposed in said slots, a sleeve mounted on the slotted end of said shaft and having grooves to receive said members, said sleeve being mounted in one of said bearings and said shaft being mounted in another bearing, means for moving said members into en-

gagement with a valve stem, a second shaft operatively connected to said first named shaft, a cutter adapted to be moved into an angle with respect to the valve, means for moving the cutter at 45 degrees with respect to the first shaft, and means for moving said cutter at right angles to said second named shaft.

3. In a valve lathe, a shaft having slots therein, valve stem engaging members 10 slidably disposed in said slots, a sleeve enclosing said members, and means for moving said members toward the longitudinal axes of said shaft.

WALTER CHAS. SCHROECK.
WILLIAM LISSMANN.
